United States Patent

Des. 234,578
Patented Mar. 25, 1975

234,578

DIGITAL CLOCK

James R. Powers, Los Angeles, Calif., assignor to Ropat-Caslon, Inc., El Segundo, Calif.

Filed Nov. 3, 1972, Ser. No. 303,640

Term of patent 7 years

Int. Cl. D10—01

U.S. Cl. D10—15

FIG. 1

FIG. 1 is a perspective view of a digital clock showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a bottom plan view thereof.

I claim:

The ornamental design for a digital clock, as shown.
